JOSEPH SACHS, OF HARTFORD, CONNECTICUT.

INCLOSED ELECTRIC SWITCH AND METHOD OF ASSEMBLING THE SAME.

Original application filed January 28, 1922, Serial No. 532,450. Divided and this application filed
August 23, 1926. Serial No. 131,041.

The invention relates particularly to a switch mechanism wherein the switch proper is inclosed in a protecting casing, ordinarily of sheet metal, and wherein there 5 is provided a cranked operating spindle for the switch rotatably mounted in bearing apertures in the side walls of the casing.

The principal object of the invention is to provide an improved means and an improved 10 method whereby the operating spindle may be readily put into its proper operative position in the casing and then conveniently and effectively held in such position.

15 In the accompanying drawing I have shown several embodiments of the mechanical features of the invention and at least two ways in which my improved method may be practiced. It will be understood, 20 however, that the drawing is intended for illustrative purposes only and is not to be construed as defining or limiting the scope of the invention, the claims forming a part of this specification being relied upon for 25 that purpose.

Of the drawing:

Fig. 1 is a front view of an inclosed switch embodying the mechanical features of the invention.

30 Fig. 2 is a vertical sectional view taken along the line 2-2 of Fig. 1.

Fig. 3 is a right side elevation.

Fig. 4 is an isometric perspective view on a reduced scale showing the initial formation 35 of the casing as shown in its final condition in Figs. 1, 2 and 3. In this view the operating spindle is shown in an intermediate position which it may assume during the assembling operation.

40 Fig. 5 is a view similar to Fig. 4, but showing the operating spindle in a position which it may assume during an alternative assembling operation.

Figs. 6 and 7 are fragmentary side elevations similar to Fig. 3 but showing different 45 embodiments of the mechanical features of the invention.

Fig. 8 is a view similar to Fig. 4, but showing an alternate embodiment of the mechanical 50 features of the invention. In this view the operating spindle is shown in an intermediate position which it may assume during the assembly operation.

Fig. 7 is a fragmentary side view showing the same construction as that shown 55 in Fig. 8, but with the casing in its final condition.

Fig. 10 is a view similar to Fig. 9, but showing an alternate embodiment of the mechanical features of the invention.

I do not limit myself to any one type of switch mechanism, but for purposes of clearly illustrating the invention I have shown one form of switch mechanism which may be used. The mechanism as shown 60 comprises a base 1 on which are mounted stationary switch contacts 2, 2 and 3, 3. Pivoted to the respective contacts 2, 2 are movable switch members 4, 4, which are adapted to engage the contacts 3, 3 when moved into 65 positions parallel with the base as shown in Fig. 2. Also mounted on the base are fuse clips 5, 5 and 6, 6, the clips 5, 5 being connected respectively with the switch contacts 2, 2. The said contacts are adapted 70 to receive cartridge fuses 7, 7 which are thus connected in series with the switches. 75

For inclosing the entire switching fuse mechanism there is provided a casing 8 having a back wall 9 and side walls 10 and 11. As illustrated, the base 1 is secured directly to the back wall 9 of the casing, but as to this, there may be variation. The casing is provided with a cover 12, preferably hinged to the casing at the bottom. The 80 cover is provided with inward extending flanges 13 which, when the cover is closed overlap the side and end walls of the casing.

For operating the switch members 4, 4 85 there is provided an operating spindle 14 comprising two aligned pivot sections 15 and 16 with a crank section 17 between them, the said crank section including crank arms 17^a and 17^b. The length of the crank section 90 17 is such that the two side walls 10 and 11 of the casing are closely adjacent the ends of the said crank section. The spindle also comprises a handle 18 at the end of one of the pivot sections such as the section 16. 100 The two side walls 10 and 11 of the casing are provided respectively with bearing apertures 19 and 20 for receiving and approximately fitting the respective pivot sections 15 and 16 of the operating spindle. When 105 the spindle is in place with its pivot sections

fitting the said bearing apertures, the handle 18 is on the exterior of the casing as clearly shown in Figs. 1 and 3. In order that the switch members 4, 4 may be moved by the 5 crank section 17 of the spindle, the said members are provided respectively with plates 21, 21 of insulating material, each plate being provided with a slot or aperture as shown at 22 for receiving the said crank 10 section 17. From the foregoing description it will be obvious that when the handle 18 is turned the switch members 4, 4 are correspondingly moved to be engaged with or disengaged from the stationary switch contacts 3, 3.

In accordance with the present invention I provide a novel and improved means and a novel and improved method whereby the operating spindle may be put in place and 20 held in place as shown in Figs. 1 to 3.

Referring particularly to Fig. 4, it will be observed that there is initially provided in the side wall 11 of the casing a slot 23 which communicates with the bearing aperture 20. This slot has a width and a length which are sufficient to permit the spindle to be moved therethrough into its operative position with the pivot sections 15 and 16 thereof fitting the respective bearing apertures 19 and 20 and with the handle 18 on the exterior of the casing adjacent the slotted side wall 11. As shown the slot extends from the front edge of the side wall. As to the exact procedure followed in moving the spindle into position, there may be some variation. The bearing aperture 19 may be slightly larger than the corresponding pivot section 15 so as to provide a limited amount of play, the spindle may be put in place as 30 illustrated in Fig. 4. In the procedure as illustrated, the pivot section 15 is first inserted into the aperture 19 while the pivot section 16 remains above the level of the front or upper edge of the wall 11. Then 40 the spindle may be swung backward or downward, the pivot section 16 moving inward through the slot 23 into its proper position in the bearing aperture 20.

The spindle may be put in place as indicated in Fig. 5. In following the procedure illustrated in Fig. 5, the spindle is moved endwise and in substantial parallelism with itself throughout the entire movement. In being thus moved the spindle assumes an intermediate position as shown in Fig. 5 and the endwise movement is continued until the pivot sections 15 and 16 enter the respective apertures 19 and 20. It will be understood that during this movement the crank section, or at least the right hand crank arm 17^b thereof, passes transversely through the slot 23.

In accordance with the invention I provide a closure associated with the casing for closing said slot 23 after the spindle is in

place, this closure also serving to hold the corresponding pivot section 16 in place in the bearing aperture 20. A further and very important function of the closure is to serve in cooperation with the casing side walls to 70 prevent or limit endwise movement of the spindle. Such movement is prevented by reason of the engagement of the said crank section at its ends with the said closure and with the side walls 10 and 11. 75

As to the exact form of closure there may be considerable variation, and the closure may be formed integrally with the casing or otherwise. However, I prefer and have illustrated a closure which is formed integrally with the side wall 11 of the casing. As shown particularly in Figs. 4 and 5, the slot 23 is formed by slitting the side wall and by bending a portion thereof adjacent the slit away from the plane of the said side 80 wall so as to form a projecting lip 24 and so as to leave the said slot. After the spindle has been put in place the lip 24 may be bent backward or returned to the plane of the side wall, the lip thus forming a closure for 85 the slot as clearly shown in Fig. 3 and serving to hold the pivot section 16 in place in its bearing aperture as also shown in the same figure. The lip also serves, as already described, to prevent endwise movement of 90 the spindle.

As already stated I do not limit myself to an integrally formed closure for the slot, but when an integrally formed closure is provided there may be some variation as 100 concerns the details thereof. In Fig. 6 there is shown a lip 25 having a dove-tailed projection 25^a thereon adapted to enter and fit a correspondingly shaped dove-tailed recess at the edge of the slot. It will be clear that 105 when the lip 25 is returned to the plane of the side wall, the projection 25^a will interlock with the said side wall thus providing increased strength. In Fig. 7 I have shown a closure for the slot in the form of two 110 separate lips 26, 26 instead of a single lip.

When there is a cover such as 12 having side flanges such as 13, the cover flange at one side is of particular advantage in conjunction with my improved construction as 115 it serves to support and protect the slot closure. As shown clearly in Fig. 3 the position of the cover flange 13 is such as to prevent the lip 23 from being bent outward.

Each of the constructions shown in Figs. 120 1 to 7 includes a slot which extends from the front edge of the casing side wall to the corresponding bearing aperture. This construction enables the operating spindle to be swung downward in position, if desired, 125 as indicated in Fig. 4. However, it is not essential to have the slot extend from the front edge of the cover, and in fact under some conditions it may be much preferable to have a slot which is closed at both ends. 130

With a closed slot there is less tendency to reduce the mechanical strength of the casing.

In Figs. 8 and 9 I have shown a construction in which there is provided a slot 27 having both of its ends closed. The slot is shown as being parallel with the back wall of the casing, but it will be understood that this position is not essential. It will also be understood that the length of the slot 26 must be at least equal to the amount of offset of the crank section 17 of the spindle so as to permit the spindle to be inserted endwise through the slot. During insertion the spindle is moved endwise and in substantial parallelism with itself into its final operative position with the pivot sections 15 and 16 respectively fitting the bearing apertures 19 and 20.

20 The closure for the slot 27 may be similar to the closures already described in conjunction with the other constructions. As shown the slot 27 is formed by slitting the side wall between the edges thereof and by bending a portion of the metal away from the plane of the side wall so as to form a projecting lip 28 and so as to leave the said slot. After the spindle has been put in place the lip 28 may be bent or returned to 30 the plane of the side wall so as to close the slot as shown in Fig. 9 and so as to hold the corresponding pivot section 16 in place and prevent endwise movement of the spindle.

35 In Fig. 10 I have shown a construction somewhat similar to that shown in Figs. 8 and 9. However, instead of providing a single lip 28 for forming the closure, I have provided four separate lips 29, 29, these being arranged on opposite sides of the bearing aperture.

It will be understood that with any of the constructions described, the spindle can be very easily and quickly put into place. 45 Primarily the spindle is inserted by moving it endwise, although with the open-ended slot construction there may be an accompanying swinging movement as shown in Fig. 4. In any case I avoid the tortuous threading of the spindle through a small bearing aperture, as has been the prior practice.

This application constitutes a division of my copending application for electric switches, Serial Number 532,450, filed January 28, 1922, allowed Oct. 6, 1925, and forfeited April 6, 1926. I do not herein claim the details of construction and the specific method as disclosed in Figs. 8 to 10 of the drawing, these being presented and claimed in my copending application for inclosed electric switch and method of assembling the same, Serial Number 131,042, filed on even date herewith.

What I claim is:

65 1. The combination with a switch com-

prising stationary contacts and an associated movable member, of a single piece switch operating spindle comprising two aligned pivot sections with an off-set crank section between them operatively connected with the 70 movable switch member and also comprising a handle at the end of one of the said pivot sections, an inclosing casing for the said switch having its opposite side walls closely adjacent the ends of the said crank 75 section of the spindle and having in the respective side walls aligned bearing apertures for receiving and approximately fitting the respective pivot sections of the spindle, the said casing also initially having in 80 one of its side walls a narrow slot communicating with the corresponding bearing aperture and having a width and a length sufficient to permit the said spindle to be moved therethrough into its operative position with the pivot sections thereof fitting the respective bearing apertures and with the handle on the exterior of the casing adjacent the slotted side wall, and a closure 85 associated with the casing for closing the 90 said slot and for holding the corresponding pivot section in place in its bearing aperture, the said closure also cooperating with the casing side walls to engage the crank section and thereby prevent endwise movement of the spindle.

2. The combination with a switch comprising stationary contacts and an associated movable member, of a single piece switch operating spindle comprising two aligned 100 pivot sections with an off-set crank section between them operatively connected with the movable switch member and also comprising a handle at the end of one of the said pivot sections, an inclosing casing for 105 the said switch having its opposite side walls closely adjacent the ends of the said crank section of the spindle and having in the respective side walls aligned bearing apertures for receiving and approximately fitting the respective pivot sections of the spindle, the said casing also initially having in one of its side walls a narrow slot 110 communicating with the corresponding bearing aperture and having a width and a length sufficient to permit the said spindle to be moved endwise and in substantial parallelism through the slot into its operative position with the pivot sections thereof fitting the respective bearing apertures and 115 with the handle on the exterior of the casing adjacent the slotted side walls, and a closure associated with the casing for closing the said slot and for holding the corresponding pivot section in place in its bearing aperture, the said closure cooperating with the casing side walls to engage the crank section and thereby prevent endwise movement of the spindle.

3. The combination with a switch com-

prising stationary contacts and an associated movable member, of a single piece switch operating spindle comprising two aligned pivot sections with an off-set crank section 5 between them operatively connected with the movable switch member and also comprising a handle at the end of one of the said pivot sections, and an inclosing casing for the said switch having its opposite side 10 walls closely adjacent the ends of the said crank section of the spindle and having in the respective side walls aligned bearing apertures for receiving and approximately fitting the respectively pivot sections of the 15 spindle, the said casing also initially having one of its side walls slotted with the metal adjacent the slit bent away from the plane of the side wall to form a projecting lip and to leave a slot in the said wall communicating with the corresponding bearing aperture, the said slot having a width and a 20 length sufficient to permit the said spindle to be moved therethrough into its operative position with the pivot sections thereof fitting the respective bearing apertures and with the handle on the exterior of the casing adjacent the slotted side wall, and the said projecting lip being adapted to be returned to the plane of the corresponding 25 side wall after the spindle is in place so as to close the slot and hold the corresponding pivot section in place in its bearing aperture and so as to also cooperate with the other parts of the said side walls to engage 30 the crank section and thereby prevent endwise movement of the spindle.

4. The combination with a switch comprising stationary contacts and an associated movable member, of a single piece switch 40 operating spindle comprising two aligned pivot sections with an off-set crank section between them operatively connected with the movable switch member and also comprising a handle at the end of one of the 45 said pivot sections, an inclosing casing for the said switch having its opposite side walls closely adjacent the end of the said crank section of the spindle and having in the respective side walls aligned bearing apertures for receiving and approximately fitting the respective pivot sections of the spindle, the said casing also initially having in one of its side walls a slot communicating 50 with the corresponding bearing aperture and having a width at least equal to the diameter of the spindle and extending from the front of the said side wall so as to permit the said spindle to be moved through the slot into its operative position with the 55 pivot sections thereof fitting the respective bearing apertures and with the handle on the exterior of the casing adjacent the slotted side wall, and a closure associated with the casing for closing the said slot and 60 for holding the corresponding pivot section 65

in place in its bearing aperture, the said closure cooperating with the casing side walls to engage the crank section and thereby prevent endwise movement of the spindle. 70

5. The combination with a switch comprising stationary contacts and an associated movable member, of a single piece switch operating spindle comprising two aligned pivot sections with an off-set crank 75 section between them operatively connected with the movable switch member and also comprising a handle at the end of one of the said pivot sections, an inclosing casing for the said switch having its opposite side walls closely adjacent the ends of the said crank section of the spindle and having in the respective side walls aligned bearing apertures for receiving and approximately fitting the 80 respective pivot sections of the spindle, the 85 said casing also initially having one of its side walls slotted from the front thereof to the bearing aperture therein with the metal adjacent the slit bent away from the plane of the side wall to form a projecting lip and 90 to leave a slot in the said wall communicating with the said bearing aperture, the said slot having a width sufficient to permit the said spindle to be moved therethrough into its operative position with the pivot 95 sections thereof fitting the respective bearing apertures and with the handle on the exterior of the casing adjacent the slotted side walls, and the said projecting lip being adapted to be returned to the plane of the 100 corresponding side wall after the spindle is in place so as to close the slot and hold the corresponding pivot section in place in its bearing aperture and so as to also cooperate with the other parts of the said side walls 105 to engage the crank section and thereby prevent endwise movement of the spindle, and a flanged front cover for the casing one of the flanges of which normally extends outside of the slotted portion of the casing wall 110 and prevents the lip from being bent outward.

6. The herein described method of assembling an electric switch inclosing casing and a single piece switch operating spindle comprising two aligned pivot sections with a crank section between them and also comprising a handle at the end of one of the said pivot sections, the said method comprising initially forming the casing with aligned bearing apertures in its opposite side walls for receiving and approximately fitting the respective pivot sections of the spindle and with a slot in one of the side walls communicating with the corresponding bearing aperture, then moving the spindle endwise and in substantial parallelism through the slot into its operative position with the pivot sections thereof fitting the respective bearing apertures and with the handle on the ex- 115 120 125 130

terior of the casing adjacent the slotted side wall, and finally when the spindle is in position providing a closure for the slot which closure holds the corresponding pivot section in place in its bearing aperture and also cooperates with the casing side walls to engage the crank section and thereby prevent endwise movement of the spindle.

7. The herein described method of assembling an electric switch inclosing casing and a single piece switch operating spindle comprising two aligned pivot sections with a crank section between them and also comprising a handle at the end of one of the said pivot sections, the said method comprising initially forming the casing with aligned bearing apertures in its opposite side walls for receiving and approximately fitting the respective pivot sections of the spindle and 0 with a slot in one of the side walls com-

municating with the corresponding bearing aperture and formed by slitting the side wall and bending a portion of the metal thereof to form a projecting lip, then moving the spindle through the slot into its 25 operative position with the pivot sections thereof fitting the respective bearing apertures and with the handle on the exterior of the casing adjacent the slotted side wall, and finally when the spindle is in position bending the said lip to return it to the plane of the corresponding side wall so as to close the slot and hold the corresponding pivot section in place in its bearing aperture, the 30 said lip cooperating with the other parts of the side walls to engage the crank section and thereby prevent endwise movement of the spindle.

JOSEPH SACHS.
